RELAY

Willis H. Gille, St. Paul, Minn., assignor to Minneapolis-Honeywell Regulator Company, Minneapolis, Minn., a corporation of Delaware

Application December 19, 1934, Serial No. 758,231

11 Claims. (Cl. 200—98)

This invention relates to relays.

An object of this invention is to provide a relay of novel construction which is extremely efficient and delicate in operation and yet easy and inexpensive to manufacture.

Another object is to provide an armature assembly in a relay that is mechanically balanced so that gravity will have no effect on the operation of the armature assembly.

10 Another object is to provide a relay having spaced coils and a pivoted armature associated therewith with means for preventing chatter and noise at the pivot of the armature.

15 A further object is to provide a relay having spaced coils and a pivoted armature associated therewith with means tending to urge the armature towards neutral position.

20 A still further object is to provide a relay having spaced coils and a pivoted armature associated therewith, having a contact arm movable between and engageable with a pair of contacts and a friction buffer mechanism to prevent rebounding of the contact arm into engagement with one contact when it is released from the 25 other contact.

Still another object is to provide a novel coil assembly construction and casing construction to minimize the amount of eddy currents existing therein.

30 Other objects and advantages will become apparent to those skilled in the art by reference to the accompanying specification, claims and drawing in which:

Fig. 1 is a top plan view of the relay of this 35 invention;

Fig. 2 is a front elevational view with a portion thereof shown in section, the section being taken along the line II—II of Fig. 3;

Fig. 3 is a vertical sectional view taken along 40 the line III—III of Fig. 2;

Fig. 4 is a bottom view of the right hand portion of the relay as shown in Fig. 2;

Fig. 5 is a detailed view of the friction buffer mechanism of this invention;

45 Fig. 6 is a diagrammatic view showing one means for controlling the operation of the relay, and

Fig. 7 is a diagrammatic view showing another means for operating the relay.

The relay of this invention is contained within a housing made up of a rear portion or enclosure 10 and a cooperating front portion or enclosure 11. When the two portions 10 and 11 of the casing are assembled together they make an overlap connection as at 12. The rear portion 10 has

laterally extending ears 13 provided with holes therein and the front portion 11 is likewise provided with laterally extending ears provided with holes therein, the holes of the ears 13 and 14 adapted to receive screws 15 for securing the 5 relay of a suitable base, not shown, and for holding the rear and front portions 10 and 11 in assembled relation.

Mounted in the casing is a pair of spaced coil assemblies. The left hand coil assembly as 10 viewed in Fig. 2 comprises a split tube 17 that is square in cross section, coil windings 18 wrapped around the split tube, upper and lower split plates 19 and 20, respectively, and flanges 21 on the tube overlying the upper and lower plates 15 19 and 20 to secure the split tube 17, the coil windings 18 and the upper and lower plates 19 and 20 in assembled relation. The front and rear portions 11 and 10 are provided with downwardly extending lugs 22 which extend through 20 notches in the lower plate 20 and which are bent over into engagement with the lower plate 20 to hold the coil assembly in place in the casing. The left hand coil as viewed in Fig. 2 has lead wires 25 and 26 extending therefrom and the 25 coil windings 18 are insulated and protected by means of insulating tape 27.

The construction of the right hand coil as viewed in Fig. 2 is the same as the left hand coil except that the right hand coil windings have 30 been designated 16 instead of 18 and the lead wires extending therefrom have been designated 23 and 24 instead of 25 and 26.

It will be noted at this point that split portions 35 of the tube 17 and upper and lower plates 19 and 20 coincide to form a continuous break in the metallic elements associated with the coil windings to prevent the flow of eddy currents therein.

By reason of the coil assembly construction and the casing construction described above, the 40 relay may be constructed of relatively inexpensive sheet metal, the parts may be easily assembled, large open spaces in communication with the surrounding atmosphere aid cooling of the coils and the formation of eddy currents in the 45 relay is greatly minimized.

Secured in the rear and front sections 10 and 11 of the casing of the relay intermediate the coil assemblies are bearings 30 having rounded portions at their inner sides. An armature is designated at 31, having downwardly extending lugs 33 adapted to receive a pivot pin 32 which is mounted in the bearings 30 of the rear and front portions 10 and 11 of the casing of the relay. Located at opposite downwardly slanting ends 50

of the armature 31 are downwardly extending cores 34 and 35 which are formed by downwardly bent lugs and which coat respectively with the coil windings 16 and 18 of the coil assemblies. 5 Extending downwardly from the center of the armature 31 is a resilient switch arm 37. Also extending downwardly from the armature 31 is a spring anchor member 38. The resilient switch arm 37 and the spring anchor member 38 are 10 secured to the armature 31 by means of rivets 39. The armature 31, the cores 34 and 35, the anchor member 38 and the switch arm 37 are so constructed and positioned about the pivot pin 32 that the armature assembly formed by these 15 members is completely balanced so that gravity will have no turning effect on the armature assembly regardless of the position in which the relay is placed. The relay will operate just as efficiently in a vertical position or any other position as in the horizontal position shown which is extremely beneficial especially where small currents are used to operate the relay.

Extending rearwardly from the bottom of the front portion 11 of the casing is a spring anchor member 40. The spring anchor members 38 and 40 are provided with holes adapted to receive the opposite ends of a spring 41. It will be noted at this point that the spring anchor members 38 and 40 are located at an angle with respect 25 to the center line of the spring 41 so that an effective knife-edge construction is afforded to give accurate operation of the instrument. It will also be noted at this point that the connection of the spring 41 to the spring anchor member 38 of the armature 31 is located at a point below the pivot pin 32 upon which the armature 31 is pivoted. The primary function of the spring 41 is to hold the armature 31 tight against the pivot pin 32 and to hold the pivot pin 32 30 tight against the bearings 30 to prevent chattering and the objectionable noises at these pivotal connections which may be occasioned by the use of A. C. current in the coils 16 and 18. Since the spring is connected below but close to the pivot pin 32, the force exerted by the spring on 35 the armature is always acting in substantially the same direction as the magnetic force exerted on the armature through cores 34 and 35. In this manner, it is assured that chattering will be reduced to a minimum since, regardless of 40 the position in which the relay is placed, there is always a force acting in one direction to hold the armature tight against the pivot pin 32.

The resilient contact arm 37 is provided at its 45 lower end with oppositely extending contacts 42 which are adapted to alternately engage adjustable stationary contacts 43 and 44. The contacts 43 and 44 are provided with screw threads which cooperate with binding posts 45 and 46 to permit 50 their proper adjustments, the binding posts 45 and 46 being suitably secured to a base not shown.

A friction snubber mechanism is generally designated at 50 and it is provided with downwardly extending ears 51 having inwardly extending concave portions 51'. The friction snubber 50 is 55 also provided with laterally extending lugs 52 and 53 which are adapted to engage alternately the upper surface of armature 31. As shown in 60 Fig. 5, the downwardly extending ears 51 are normally spread outwardly. When the friction snubber mechanism 50 is assembled in the relay, the concave indentations 51' engage the inner 65 rounded portions of bearings 30 to form surface contacts and by reason of this surface engage-

ment and the outwardly extending force of ears 51, a frictional engagement is maintained between the friction snubber 50 and the bearings 30 so that movement of the friction snubber 50 with respect to the casing is retarded.

By referring to Fig. 2, it will be noted that there is a lost motion between the friction snubber device 50 and the armature 31. Assume that the armature 31 is moved in a counter-clockwise direction about its pivot 32, contact 42 of the 10 contact arm 37 will engage the stationary contact 43 and due to the resiliency of contact arm 37, a force is built up therein tending to urge the armature 31 in a clockwise direction. This counter-clockwise movement of armature 31 will 15 cause the armature 31 to engage the right hand lug 52 of friction snubber 50 to also move the friction snubber 50 in a counter-clockwise direction. When the armature 31 is in this counter-clockwise position, a lost motion will then exist 20 between the armature 31 and the left hand lug 53 of the friction snubber 50. Upon electrically balancing the coil windings 16 and 18 in a manner to be pointed out hereafter, so that the armature is moved to its mid position, the force built 25 up in the resilient contact arm 37 will be expended to tend to snap the contact 42 into engagement with the stationary contact 44. Such movement would be extremely detrimental in the 30 operation of this type of relay and this movement is effectively prevented by means of the friction snubber 50. Movement of the armature 31 in an amount sufficient to move contact 42 away from stationary contact 43 to its mid position causes the taking up of the lost motion between 35 the armature 31 and the left hand lug 53 of friction snubber 50. Further movement beyond the mid-position is resisted by the action of the friction snubber so that the resilient contact arm cannot be snapped into engagement with the contact 44.

From the above, it is seen that the contact 42 of the contact arm 37 may be moved freely from engagement with the contact 43 to its mid-position because of the lost motion between the lug 53 and the armature 31 but further movement thereof into possible engagement with the contact 44 is prevented by the friction snubber 50.

Fig. 6 diagrammatically shows one method of operating the relay of this invention. The right and left hand coils are diagrammatically shown at 16 and 18 respectively and cooperating therewith are the cores 34 and 35 respectively secured to the armature 31. Extending downwardly from the armature 31 is the contact arm 37 which 55 alternately engages contact 43 or contact 44. As above, lead wires 23 and 24 extend from the coil 16 and lead wires 25 and 26 extend from the coil 18. Lead wires 23 and 25 are connected together and to a wire 55 which is in turn connected to one end of a protective resistance 56. The other end of the protective resistance 56 is connected by means of a wire 57 to a switch arm 58. Switch arm 58 is moved by some means 59 to alternately engage contacts 60 or 61. Contact 60 is connected by a wire 62 to a wire 63 which in turn is connected to one end of secondary 65 of a step down transformer 66. Contact 61 is connected by means of a wire 64 to the other end of secondary 65 to the step down transformer 66. Lead wire 26 is connected to wire 63 and lead wire 24 is connected to the secondary 65 at the point where wire 64 is connected thereto. Step down transformer 66 is provided with a primary 67 which is energized by line wires 68 and 69.

leading from some power source not shown. An operating circuit for some device, not shown, is completed through wires 70, 71 and 72 connected to contact 43, contact 44 and contact arm 37 respectively.

With the switch arm 58 in the mid-position, as shown in Fig. 6, the coils 16 and 18 are equally energized to maintain the armature 31 in its neutral or mid-position due to the fact that these coils are connected in series by wires 24, 23, 25, 26 and 63 with the secondary 65 of step down transformer 66. When the operating means 59 moves switch arm 58 into engagement with contact 60, a shunting circuit around the coil 18 is completed to substantially short circuit the same by reason of the wires 62, 63, contact 60, switch arm 58, wire 57, protective resistance 56 and wire 55. By completing this shunting circuit, the amount of current passing through the coil 18 is decreased and the amount of current passing through the coil 16 is increased whereby armature 31 is moved in a clockwise direction to move contact 42 of the contact arm 37 into engagement with the stationary contact 44 to complete an operating circuit from wire 72 through contact arm 37, contact 42, contact 44 and wire 71. Upon movement of the switch arm 58 to a point intermediate the contacts 60 and 61, the shunting circuit above described will be broken and the coils 16 and 18 will be equally energized to move the switch arm 37 to its mid-position out of engagement with contacts 43 and 44. Movement of the switch arm 58 by means of operating means 59 into engagement with the contact 61 completes a shunting circuit around the coil 16 to short circuit the same through wires 64, contact 61, switch arm 58, wire 57, protective resistance 56 and wire 55 whereby the current or the energy in coil 18 is increased and the energy in coil 16 is decreased to move the armature 31 in a counter-clockwise direction to cause contact arm 37 to move contact 42 in engagement with contact 43 to complete an operating circuit from wire 72, contact 42, contact 43 to wire 70. Again, movement of switch arm 58 to a point intermediate the contacts 60 and 61 will break the last mentioned shunting circuit to equally energize the coils 16 and 18 to move contact 42 out of engagement with contact 43.

In the mode of operation shown in Fig. 6, it will be noted that the contact arm 37 is maintained in its mid-position by supplying equal amounts of electrical energy to the coils 16 and 18 and is moved into engagement with the contact 43 by increasing the electrical energy in coil 18 and decreasing the energy in coil 16 and is moved into engagement with contact 44 by increasing the energy in coil 16 and decreasing the energy in coil 18. By reason of this construction, the armature 31 is electrically positioned in its mid-position by reason of the equal energization of coils 16 and 18.

Referring now to Fig. 7, there is a different manner disclosed for operating the relay of this invention. Fig. 7 is similar to Fig. 6 in that the same coils 16 and 18, lead wires 23, 24, 25 and 26 therefor, cores 34 and 35, armature 31, contact arm 37, contacts 42, 43 and 44 are used. The mode of operation of the mechanism shown in Fig. 7 differs from that shown in Fig. 6 in that when the armature 31 and contact arm 37 of Fig. 7 are in the mid-position as shown, the coils 16 and 18 are not energized while in Fig. 6, they are equally energized. Lead wire 23 is connected to a stationary contact 73 and lead wire 25 is con-

nected to a stationary contact 76. Alternately engaging these contacts 75 and 76 is switch arm 77 operated by some means designated at 78. Switch arm 77 is connected by means of a wire 79 to one end of a secondary 80 of a step down transformer 81. The other end of the secondary 80 is connected to the lead wires 24 and 26. Step down transformer 81 is provided with a primary 82 which receives its energy from power lines 83 and 84 which are connected to some source of power, not shown. A wire 87 is connected to the contact arm 37 and wires 85 and 86 are connected respectively to contacts 43 and 44. Wires 85, 86 and 87 lead to and control some device not shown.

With the switch arm 77 in the position shown in Fig. 7 midway between the contacts 75 and 76, no circuits are completed and the coils 16 and 18 remain unenergized and the contact arm 37 is maintained midway between the contacts 43 and 44. Movement of switch arm 77 into engagement with the contact 75 by means of the operating means 78 completes a circuit from the secondary 80 through wires 79, switch arm 77, contact 75, wire 23, coil 16, and wire 24 back to the secondary 80 in a clockwise direction to cause contact 42 to engage contact 44 to complete an operating circuit through wires 87, switch arm 37, contacts 42 and 44, and wire 86. Movement of switch arm 77 out of engagement with the contact 75 to the mid-position shown in Fig. 7 breaks the above circuit and the armature 31 is moved to its mid-position by means of the spring 41 shown in Figs. 2 and 3. Movement of switch arm 77 by means of operating means 78 into engagement with the contact 76 completes a circuit from secondary 80 of step down transformer 81 through wire 79, switch arm 77, contact 76, wire 25, coil 18 and wire 26 back to the secondary 80 energizing the coil 18 to move the armature 31 in a counter-clockwise direction to cause contact 42 to engage contact 43 to complete an operating circuit through wires 87, contact arm 37, contact 42, contact 43 and wire 85. Again, when switch arm 77 is moved out of engagement with contact 76 to the mid-position shown in Fig. 7, the coil 18 is deenergized and the armature 31 and the contact arm 37 will move to their mid-positions by means of spring 41 as shown in Figs. 2 and 3.

From the above references to Figs. 6 and 7, it is seen that the armature 31 is moved to one position or the other upon an unbalancing of the energy in the coils 16 and 18 whether the unbalancing is caused by increasing the energy in one coil and decreasing it in another or by solely energizing one coil and not affecting the other coil. Also, by referring to Figs. 6 and 7, it is seen that the armature 31 is moved to its mid-position upon balancing of the coils 16 and 18 regardless of whether the coils 16 and 18 are equally energized or whether they are not energized. Therefore, it is within the contemplation of this invention to use the term "balancing" to mean equally energizing the coils 16 and 18 or not energizing the coils 16 and 18 and likewise, the term "unbalancing" may mean increasing the energy in one coil and decreasing the energy in the other coil or applying energy to one coil and not applying energy to the other coil. On both instances, the final result is the same.

As above stated, the primary use of spring 41 is to prevent chattering and objectional noises at the pivotal connections of armature 31. When it is preferable to use the mode of operation illus-

70

75

trated in Fig. 6, no means are required to return the armature to its mid-position because this is accomplished by the equal energization of the coils 16 and 18. Therefore, the upper connection 5 of spring 44 with the anchor member 38 is made as close to the pivot connection 32 of the armature 31 as possible so that the spring 44 will have practically no biasing effect on the armature 31 to urge the armature 31 to its mid-position.

10 However, if it is desirable to use the mode of operation illustrated in Fig. 7, some means must be provided for urging the armature 31 to its mid-position when the coils 16 and 18 thereof are not energized. In this type of construction, the spring 16 41 which prevents chatter in the pivotal connections 32 also affords a means for returning the armature to its mid-position. By lowering the upper connection of spring 41 to the spring anchor member 38 away from the pivot pin 32, this 20 centering action of the spring 41 is increased. Therefore, it is seen that by increasing the effective lever arm of spring anchor member 38 acted upon by the spring 41, the spring 41 performs a dual function that of preventing chattering at 25 the pivot and that of restoring the armature to its mid-position upon balancing or deenergization of both coils 16 and 18.

In both modes of operation, as shown in Figs. 6 and 7, the friction buffer device 50 is used to 30 prevent rebounding of the contact arm 37 from one contact to the other upon electrically balancing the coils 16 and 18.

From the above, it is seen that I have provided a relay of novel construction which is extremely 35 sensitive and accurate in operation, which is easy and inexpensive to manufacture, which allows for ready cooling of the coils, which minimizes the amount of eddy currents existing therein, which is noiseless in operation and which prevents faulty 40 operation caused by the rebounding of the contact arm from one contact to another upon the electrical balancing of the coils thereof.

While one embodiment of this invention has been shown and described, it is obvious that many 45 modifications may be apparent to those skilled in the art and consequently this invention is to be limited only by the scope of the appended claims and the prior art.

I claim as my invention:

50 1. In a relay of the class described, a pair of coils, an armature associated therewith for operation thereby, a contact arm carried by said armature, a pair of spaced contacts engageable by said contact arm, said contact arm engaging one or the other of said contacts by the selective unbalancing of said coils and positioned intermediate said contacts by the balancing of said coils, and means for preventing travel of said contact arm beyond said intermediate position upon balancing of said coils but permitting free movement to said intermediate position, said means comprising a frictionally mounted movable abutment for said armature.

65 2. In a relay of the class described, a pair of coils, a pivotally mounted armature associated therewith for operation thereby, a contact arm carried by said armature, a pair of spaced contacts engageable by said contact arm, said contact arm engaging one or the other of said contacts 70 by the selective unbalancing of said coils and positioned intermediate said contacts by the balancing of said coils, and means associated with said armature for preventing travel of said contact arm beyond said intermediate position upon balancing of said coils, said means comprising a

frictionally mounted movable abutment adapted to bear against said armature after a predetermined movement of the same from contact making position.

3. In a relay of the class described, a pair of coils, a pivotally mounted armature associated therewith for operation thereby, a contact arm carried by said armature, a pair of spaced contacts engageable by said contact arm, said contact arm engaging one or the other of said contacts by the selective unbalancing of said coils and positioned intermediate said contacts by the balancing of said coils, and means frictionally mounted on said pivotal mounting of said armature for preventing travel of said contact arm beyond said intermediate position upon balancing of said coils.

4. In a relay of the class described, a pair of coils, a pivotally mounted armature associated therewith for operation thereby, a contact arm 20 carried by said armature, a pair of spaced contacts engageable by said contact arm, said contact arm engaging one or the other of said contacts by the selective unbalancing of said coils and positioned intermediate said contacts by the balancing of said coils, and means comprising a frictionally mounted movable abutment having a lost motion connection with said armature for preventing travel of said contact arm beyond said intermediate position upon balancing of said 25 coils but permitting free movement to substantially said intermediate position.

5. In a relay of the class described, a casing, a pair of coils mounted therein, an armature associated with said coils for operation thereby, a pivotal connection between said armature and said casing, a contact arm carried by said armature, a pair of contacts engageable by said contact arm, said contact arm engaging one or the other of said contacts by the selective unbalancing of said coils and positioned intermediate of said contacts by the balancing of said coils, and means mounted on said pivotal connection in frictional engagement with said casing and having a lost motion connection with said armature for preventing travel of said contact arm beyond said intermediate position upon balancing of said coils but permitting free movement of said contact arm to substantially said intermediate position.

6. In a relay of the class described, a pair of coils having passages extending therethrough, a pivoted armature including a pair of cores extending into said coils for operation thereby, a contact arm carried by said armature, a pair of spaced contacts engageable by said contact arm, said contact arm engaging one or the other of said contacts by the selective unbalancing of said coils and positioned intermediate said contacts by the balancing of said coils, and said armature and said contact arm being disposed about the pivot point symmetrically to all lines through the pivot point so that gravity has no effect upon the operation of the relay regardless of the angular position thereof, and springs connected to said armature and anchored between said coils to maintain said armature in said intermediate position when said coils are balanced.

7. In a relay of the class described, a pair of coils having passages extending therethrough, a pivoted armature including a pair of cores extending into said coils for operation thereby, a contact arm carried by said armature, and a pair of spaced contacts engageable by said contact arm, said contact arm engaging one or the other

of said contacts by the selective unbalancing of said coils and positioned intermediate said contacts by the balancing of said coils, and said armature and said contact arm being disposed about the pivot point symmetrically to all lines through the pivot point so that gravity has no effect upon the operation of the relay regardless of the angular position thereof.

8. In a relay, a pair of coils having openings therein, mounting means for said coils, an armature formed of a single piece of elongated sheet metal, said armature having a projecting portion at an intermediate point thereof and at each end, all of said projecting portions being bent perpendicularly to said base, the intermediate portion being pivotally connected to said mounting means to pivotally support said armature and each of the end portions being disposed so as to extend into the opening of one of said coils to form a core member for said coil.

9. In a relay, a pair of coils having openings therein, mounting means for said coils, an armature formed of a single piece of elongated sheet metal, said armature having a pair of projecting portions on opposite sides of said armature at an intermediate point thereof and at each end, all of said pairs of projecting portions being bent perpendicularly to said base, the intermediate pair being pivotally connected to said mounting means to pivotally support said armature and

each of the end pairs being disposed so as to extend into the opening of one of said coils to form a core member for said coil.

10. In a relay, a pair of relay coils, each having a passage therethrough, a sheet metal casing having two component parts partially enclosing said coils, each of said parts having a pair of lugs at each end thereof, which lugs are bent over to engage opposite ends of said coils and retain the coils in assembled relationship, a pivot pin extending between said parts intermediate said coils, and an armature pivotally secured at its midpoint to said pivot pin, said armature having two core members each of which extends into the passage of one of said coils.

11. In a relay, a pair of relay coils, each having a passage therethrough, a sheet metal casing having two component parts partially enclosing said coils, each of said parts having a pair of lugs at each end thereof, which lugs are bent over to engage opposite ends of said coils and retain the coils in assembled relationship, a pivot pin extending between said parts intermediate said coils, and an armature pivotally secured at its midpoint to said pivot pin, said armature having two core members each of which extends into the passage of one of said coils, said armature, including said core members, being formed of a unitary piece of sheet metal.

WILLIS H. GILLE. 30
